Filed June 23, 1965, Ser. No. 85,873

Term of patent 14 years

(Cl. D26—14)

FIG. 1

FIG. 2

FIG. 3

FIGURE 1 is a front perspective view of a two piece cover for a stereo tape recorder or similar article, showing my new design in assembled position on a tape recorder;

FIGURE 2 is a side perspective view of one of the halves of the cover removed from the recorder and turned 90 degrees, showing the speaker grill housed therein; and

FIGURE 3 is a front perspective view of the same. The broken line showing of a representative tape recorder in FIGURE 1 is for illustrative purposes only.

I claim:

The ornamental design for a two piece cover for a stereo tape recorder or similar article, substantially as shown and described.
